UNITED STATES PATENT OFFICE

ARTHUR H. PRICE, OF NEOSHO FALLS, KANSAS

WIRE-FASTENING MEANS

Application filed January 9, 1930. Serial No. 419,676.

This invention relates to improvements in staples designed primarily for use in the construction of fences and to the method of securing fence wire to posts.

5 The primary object of the present invention is to provide an improved form of staple which may be so secured after being driven into a post over a wire strand forming a part of a fence line, that it cannot be drawn from the post by the application of pressure to the wire strand which it holds in place.

With the ordinary type of staple the application of a sufficiently heavy weight to a wire strand of a fence which the staple may 15 be holding in position against a post, will result in the extraction of the staple and consequently the breaking down of the fence. This occurs frequently on farms or ranges where animals press against the wires of the 20 fence lines.

A wire fence wherein the strands of wire are held in place by staples of the character embodying the present invention and secured in the manner hereinafter described cannot 25 be broken down by the application of force to the wire strands as the staples are securely held against removal.

The invention will be best understood from a consideration of the following detailed description taken in connection with the accompanying drawing forming part of this specification, with the understanding, however, that the invention is not confined to any strict conformity with the showing of the drawing 35 but may be changed or modified so long as such changes or modifications mark no material departure from the salient features of the invention as expressed in the appended claims.

40 In the drawing:

Figure 1 is a view in front elevation of a post showing a staple in position therein holding a wire strand in the manner hereinafter described.

45 Figure 2 is a sectional view taken on the line 2-2 of Figure 1.

Figure 3 is a sectional view taken on the line 3-3 of Figure 2.

50 Figure 4 is a detailed view of a modified form of the staple.

Referring more particularly to the drawing wherein like numerals of reference indicate corresponding parts throughout the several views, the numeral 1 indicates a fence post across one face of which the wire strand 55 2 of a fence line is secured.

The staple embodying the present invention is indicated generally by the numeral 3. As shown the main body portion of this staple is of the usual design, it consisting of 60 a pair of relatively long legs 4 connected at one end by the rounded yoke portion 5.

Spaced from the yoke portion 5 of the staple and connecting the legs 4 thereof is a bar 6 thus forming beneath the yoke 5 the 65 eye 7.

When in use the wire strand 2 of the fence is drawn across the post, the staple 3 being driven into the post with the legs 4 straddling the strand, in the usual manner. The bar 70 6 of the staple contacts with the wire strand and forces it against the post body thus leaving the eye 7 standing out from the post.

A short tie wire 8 is then passed through the eye 7 the ends being brought around to the opposite side of the post where they are twisted together as indicated at 9, one end 75 of the wire being passed under the strand 2 while the other passes over it as is clearly shown in Figure 1.

80 From the foregoing description it will be readily seen that with the present staple secured to the post by the tie wire 8 in the manner described its extraction from the post cannot be brought about by the application 85 of pressure to the wire strand 2. In order to remove the staple the tie wire 8 must first be broken.

The form of the staple shown in Figure 3 has the bar 6 directly between the legs 4 of 90 the staple whereas in Figure 4 this bar which is here indicated by the numeral 10 lies across the staple legs here indicated by the numerals 11, to which legs it is welded as indicated at 12. The use of this modified form 95 of the staple is exactly the same as described in connection with the staple 3 as will be readily understood.

Having thus described my invention, what I claim is:

1. In combination in a wire fence construction, a staple adapted to secure a fence wire to a post, having a pair of post penetrating legs and a permanently formed eye at the outer ends of said legs, one side of said eye extending across and holding a wire strand in contact with the post when the legs are driven thereto, and a tie wire passed through said eye and secured about said post.
- 10 2. In combination in a wire fence construction, a staple adapted to secure a fence wire to a post, having a pair of post penetrating legs and an eye at the outer ends of said legs, one side of said eye holding a wire strand in contact with the post when the legs are driven thereto, and a tie wire passed through said eye and secured about said post, said tie wire extending about the post with one side above and the other side passing beneath the fence wire secured thereto.

In testimony whereof I hereunto affix my signature.

ARTHUR H. PRICE.
